(57) **CLAIM**

I claim the ornamental design for a cord fastener, as shown and described.

DESCRIPTION

FIG. 1 is a front right perspective view of the cord fastener, shown in use;

FIG. 2 is another front right perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

The evenly dashed broken lines shown in the drawings illustrate portions of the cord fastener and forms no part of the claimed design. The dash-dot lines illustrate boundaries of the design and forms no part of the claimed design.

1 Claim, 5 Drawing Sheets(56)
